MECHANISM FOR THE MANUFACTURE OF ENVELOPES WITH PASTED-IN WINDOWS

Alfred Winkler and Max Dünnebier,
Neuwied, Germany

Application November 25, 1930, Serial No. 498,022
In Germany November 25, 1929

9 Claims. (Cl. 93—61)

This invention relates to mechanism for the manufacture of envelopes with pasted-in windows or with internal linings.

The pasting-in of transparent windows or of a special lining paper into envelopes, flat bags and similar articles has heretofore been effected prior to the folding in a special operation, preceded in the case of window pasting by the stamping out of the window opening in a separate operation. 5 The pasting-in of the windows or of the lining paper has heretofore been effected by the use of special machines, as well as by hand work. This results not only in increasing the cost and the difficulty of the entire manufacturing process, but 10 even when separate machines are used for pasting in the window or the lining, the quality or uniformity of the goods is not improved because it is necessary to again stack the envelopes in the gumming machine each time so that even with 15 the most skillful operators, irregularities result, thus causing a lack of neatness in the finished work, and also entailing a great deal of waste.

One object of the present invention is to provide means whereby the stamping out of the window openings and the pasting in of the windows, or the pasting in of the lining is effected either in 25 one operation with the folding of the envelopes or with the gumming of the closure flaps and the folding of the envelopes. In addition to a substantial reduction in the manufacturing cost this results in the production of uniform goods with a minimum amount of waste, because the blanks are handled with only a single stacking in the machine and because the blanks are effectively 30 guided from the beginning of the manufacturing process until its end.

A further object is the provision of means whereby the feeding of the windows or of the lining paper to the blank, and its pasting thereon takes place by a continuous revolving suction roller which is so driven that its revolving speed coincides with the speed at which the blank 35 is moving.

On the drawings an example of the mechanism 40 according to the invention is shown. In this connection it is assumed that an envelope roller folding machine combined directly with a gum spreading machine is connected with the means for stamping out the window opening and pasting on the window or for pasting on the lining paper.

On the drawing, Fig. 1 is a side elevation partly in section of the left-hand portion of the machine, and Fig. 1a is a similar view of the right-hand portion of the same machine.

At Figs. 1, 1a of the drawing, A is the blank feeding and gumming mechanism, B is the gum-drying belts, C is the mechanism for the application of the windows and inner linings, D is the folding mechanism, and E is the receiving and stacking mechanism for the completed envelopes.

In the mechanism A, which is preferably of the form shown in our prior U. S. Patent No. 1,396,906, or of other like form, the envelope blanks 30 are carried in a stack *a* from which they are fed by 10 a sucker device 31 and are carried in overlapping relation between the rollers 32, 32' to the rollers 33, 33' to the rollers 34, 34' by which they are fed to the gumming belts 35, 35', the former of which are carried on rollers 36, 37 while the latter are carried on rollers 38, 39, 40; a gumming device 42 cooperating with a support 41 in the known manner. From the gumming belts 35, 35' the blanks pass to the drying belts 1, 1' as in the machine shown in the said patent. In the present machine the belts 1 are carried on pulleys 41 and 43 and over guide pulleys 46, 45 and 44 and over a support 54, while the belts 1' are carried on guide pulleys 53, 52, 51, 50, 49, and 48.

The belts 1 and 1' carry the blanks from the gum spreading machine with such blanks arranged in overlapping relation to expose only a little more than the gummed portions thereof. Above the belt 1, are provided adjustable delivery rollers 3 which are mounted in the known manner by means of a stem 3' adjustably secured in a bracket on a cross-bar 3'', and which rollers deliver the blanks successively to an intermediate belt 4 and to counter-rollers 5, 6, and 7 co-operating therewith. This belt 4 is carried on pulleys 35 55, 56, has a supporting table 57 and is driven at such a speed that when it receives the closely overlapping blanks it pulls them sufficiently far apart to expose the surface intended for the window and also exposes the corners which lie to 40 the rear as regards the direction of movement of the blank and which are formed by the unfolded closing flaps and the side flaps. Each individual blank is then received by the roller pair 8, 9 revolving at the same speed as the belt 4 and is 45 conveyed such a distance that its corners lying in front as regards the direction of movement are brought to within a slight distance from the forward swinging pair of adjusting fingers 10 actuated by a crank 10' and a connecting rod 10''. 50 Then the rear swinging adjusting fingers 11 engage the said rear corners and convey the blank forward until all four of said corners are engaged by the two adjusting finger pairs 10 and 11, the finger pairs 11 being advanced with the roller 55

pair 8, 9 by movement of a carrier having a toothed rack 59 engaged and actuated by a pinion 60, after the fingers 11 have been swung into engagement with the blank by means of the crank 11' and its operating rod 11''. The blank is thus accurately adjusted in the longitudinal and crosswise directions. In this straightened out position the work comes to a stop temporarily, and this is utilized for the stamping out of the window opening by means of the stamping devices 12 which comprises a movable cutting member 12' carried on a member 61 mounted on a slide 62 working in a vertical guide 63 which latter is connected to a lever 65 actuated at the proper time by a link 66 in any suitable or well-known manner. After the window opening is thus formed the blank is seized by the two rollers 13 and 14 the upper (14) of which is suitably recessed or notched out at 14' to receive the bottom flap point at the proper time, and the blank is then fed to a device for applying the adhesive for pasting on the window. This device consists of a type roller 15 which receives the adhesive from an adhesive container 18 by means of a coating roller 16 and a lifting roller 17. The blank is provided in this manner with adhesive all around the window opening and is now guided by means of sets of cooperating rollers comprising lower rollers 10 and upper swinging rollers 10' to the window pasting device consisting of a roller pair 19 and 20, whose upper roller 19 is provided with suction means and seizes the window sheet with the aid of suction openings 21 in a duct 11, and conveys it to the blank between the rollers 19, 20. For that purpose the roller 19 is so driven that its circumferential speed coincides with the speed at which the blank is moving and is so timed that it places the window sheet on the window opening in exactly the right place and presses it on at the same time. The blank which is now provided with the window may then be conducted, through a drying device if this is necessary, or to the conveying belts 23 and guide rollers 22 of the folding machine. When envelopes with pasted-in lining are to be manufactured, the operation is exactly the same as described above, and all that is necessary is to disconnect or stop the stamping device 12 and use a gumming type 15 of a contour suitable for the purpose. In the example shown it is assumed that the blanks are fed from gum spreading mechanism for the application of the gum to the closing flaps, but the blanks may of course be fed in the proper overlapping relation direct from a stack by feed mechanism of any suitable or well known form. In the example drawn it is assumed that the sheet used for the window or for the lining is taken directly from a paper roll 28 by intermittently operated roller pairs 26, 27, and by means of a belt 12 carried on the said roller 19 and over guide pulleys 73 and 74, and cooperating with a supporting table 75 and with rollers 24, 25. Cutting means comprising a lower fixed blade 29 and an upper movable blade 29' are also provided to sever the paper strip 11 from the said roll 28, as the blade 29 is lowered at the proper time by the cam or like mechanism shown in dotted lines at 16, 16' with a connecting rod 16 extending to the blade 29. The intermittent motion of the roller 26 is effected through the medium of a shaft 125 which by means of skew gears 18, 19 imparts continuous rotation to a shaft 88 which carries a disc 81 for the actuation of a Geneva

wheel 83 whose shaft 82 carries a gear 84 in mesh with a gear 85 which is mounted on a bracket 87 and is secured to the same shaft as another gear 85' which latter meshes with and imparts intermittent rotary motion to a gear 86 on the shaft 5 of the roller 26. Instead of this an arrangement can also be used which takes the finished window or lining sheet from a stack and feeds it to the suction roller 19. While being carried upon the belt 23 the blanks may be subjected to the action 10 of suitable drying apparatus comprising a duct 88, a chamber 89, and air outlets 90, or other apparatus of well-known form. This drying apparatus 88, 89 forms no part of the present invention and is of the conventional form commonly 15 employed for drying the gum on envelope flaps and for other like purposes in machines of this general type.

The envelope folding, receiving and stacking apparatus shown at D, E, Fig. 1 of the drawing is of a type well known in the art, and the specific parts of this mechanism form no part of the present invention and are shown here only for the purpose of illustration or example and to provide a complete disclosure of the entire machine. The folding mechanism D and the receiving and stacking mechanism E, may be of the form shown in our prior U. S. Patent No. 1,884,468 or in the patent to Novick No. 1,807,867.

From the belt 23 the blanks pass between rollers 81, 82 actuated by a gear 129 and in the well known manner the blanks are adjusted or straightened by means of the well-known swinging fingers 93, 94 before passing to the roller 95, 96 and as the blanks are advanced towards the left in Fig. 1, the folding appliances 101, 97, 98, 102 perform their proper functions after which the blanks pass between the rollers 99, 100 and between the rollers 103, 104, and after passing beneath the gumming sector 105, the blanks pass between the rollers 106, 107 and are engaged by the flap-folding member 110 and by actuation of the parts 108, 109, 109', 111, 113 and 114 in the known manner the completed envelopes are received by the delivery drum 115 having the envelope-engaging members 115', and the guide 116 so that the envelopes are delivered by the member 117 and the rotary member 118 to the stack 449

For the actuation of the various parts of the machine the aforesaid shaft 125 is provided with bevel gears 123, 121, 122 for the operation of a transverse shaft 128 and a longitudinal shaft 124 which latter in turn actuates a transverse shaft 128 through the medium of the bevel gears 126, 127. The said shaft 125 is also provided with bevel gears 131, 132 for the actuation of a transverse shaft 130 which latter imparts movement to a longitudinal shaft 135 through the medium of skew gears 133, 134 and the said shaft 135 in turn drives a worm 136 which actuates a worm wheel 137 on the shaft of the pulley 43 carrying the drying belts. 50 55 60

What we claim is:

1. In an envelope folding machine, mechanism 65 for the provision of pasted-in windows interposed between mechanism for feeding the blanks in overlapping relation and mechanism for folding the flaps, comprising means for drawing the blanks away from each other, means for adjusting the position of the blanks, means for stamping out the window openings in the adjusted blanks, means for the application of gum to the blanks, means for the application of the windows to said openings and means for receiving and 70 75 75

conveying the individual blanks directly to the folding mechanism.

2. In an envelope folding machine, mechanism for the provision of pasted-in windows interposed between mechanism for feeding the blanks in overlapping relation and mechanism for folding the flaps, comprising means for drawing out the blanks to expose the front and rear corners thereof between adjacent flaps, means for engaging 5 said corners to adjust the blanks in a longitudinal and crosswise direction, means for stamping out the window opening in the adjusted blanks, gum typing means for the application of adhesive to the blanks, rotary means for the application of 10 window paper to the blanks and means for receiving and conveying the individual blanks directly to the folding mechanism.

3. In an envelope folding machine, mechanism for the provision of pasted-in windows interposed 20 between mechanism for feeding the blanks in overlapping relation and mechanism for folding the flaps, comprising means for drawing the blanks successively away from each other, means for adjusting the position of the blanks, means for stamping out the window opening in the adjusted blanks, typing means for the application 25 of gum to the blanks, means for the delivery and application of the windows to said openings and means for receiving and conveying the blanks 30 to the folding mechanism.

4. In an envelope folding machine, mechanism for the provision of pasted-in windows interposed 35 between mechanism for spreading the gum on the flaps of the envelopes and mechanism for folding the flaps, comprising means for conveying the blanks in closely overlapping relation from the gum spreading mechanism, means for drawing out the blanks successively to expose the front and rear corners thereof between adjacent flaps, 40 means for engaging said corners to adjust the blanks in a longitudinal and crosswise direction, means for stamping out the window opening in the adjusted blanks, gum typing means for the application of adhesive to the blanks, rotary 45 means for the application of window paper to the adhesive upon the blanks and means for receiving and conveying the blanks to the folding mechanism.

5. In an envelope folding machine, mechanism 50 for the provision of pasted-in windows interposed between the mechanism for spreading the gum on the flaps of the envelopes and the mechanism for folding the flaps, comprising means for feeding the blanks from the gum spreading 55 mechanism, movable fingers for engaging the corners of the blanks to adjust them in position, means for forming the window opening in the blanks while engaged by said fingers, rotary gum typing mechanism for the application of adhesive to the blanks, means for 60 separating the blanks, means for feeding the blanks beneath said gum typing mechanism, rotary means for the application of window paper to the blanks, means for severing the said paper into lengths and means for receiving the individual blanks with 65 the said paper thereon and for delivering same directly to the envelope folding mechanism.

6. In an envelope folding machine, mechanism for the provision of pasted-in windows interposed between the mechanism for spreading the gum on the flaps of the envelopes and the mechanism for folding the flaps, comprising means for 5 intermittently conveying the envelope blanks from the gumming mechanism to the folding mechanism, means for separating the blanks during such conveyance, means for forming the window openings during the intermittent stoppage 10 of the blanks, means for the application of adhesive to the blanks, a suction roller for the application of window paper to the adhesive upon the blanks and means for separating the window paper into lengths for delivery to said suction 15 mechanism.

7. In an envelope folding machine, mechanism for the provision of pasted-in windows interposed between the mechanism for spreading the gum on the flaps of the envelopes and the mechanism for folding the flaps, comprising means for 20 feeding the blanks from the gum spreading mechanism in closely overlapping relation, means for successively drawing out the blanks, movable fingers for engaging the corners of the drawn out 25 blanks to adjust them in position, stamping means for forming the window opening in the blanks while engaged by said fingers, rotary gum typing mechanism for the application of adhesive to the 30 blanks, means for feeding the blanks beneath said gum typing mechanism and a rotary cylinder for the application of window paper to the blanks, means for severing the said paper into lengths and means for receiving the blanks with the said paper 35 thereon and for delivering same to the envelope folding mechanism.

8. In an envelope folding machine, mechanism for the provision of pasted-in windows interposed 40 between the mechanism for spreading the gum on the flaps of the envelopes and the mechanism for folding the flaps, comprising means for conveying the envelope blanks from the gumming mechanism to the folding mechanism, means for separating the blanks during such conveyance, means for forming the window openings, means 45 for the application of adhesive to the blanks after the formation of said openings, rotary suction mechanism for the application of window paper to the adhesive upon the blanks, means for separating the window paper into lengths for delivery to said suction mechanism, and a supply 50 roll for the supply of such paper to the separating means.

9. A machine for making window envelopes comprising mechanism for advancing a series of 55 blanks in overlapping relation, means for detaching the foremost blank of said series and speeding it up so as to space it from said series, means for temporarily arresting the so detached blank, a punch and die mechanism for cutting 60 a window opening therein, means for causing the punched blank to resume its forward movement, and means for acting on the moving blank to fold the same into an envelope.

ALFRED WINKLER. 65
MAX DÜNNEBIER.
